UNITED STATES PATENT OFFICE.

WILLIAM R. CAMPBELL, OF LANCASTER, OHIO.

CAPPING-OFF STICK.

1,257,975.

Specification of Letters Patent. Patented Mar. 5, 1918.

Application filed October 6, 1916. Serial No. 124,087.

To all whom it may concern:

Be it known that I, WILLIAM R. CAMPBELL, a citizen of the United States, and a resident of Lancaster, State of Ohio, have invented certain new and useful Improvements in Capping-Off Sticks; and I do hereby declare the following to be a full, clear, and exact description of the invention, such as will enable others skilled in the art to which it appertains to make and use the same.

My invention relates to an improvement in capping off stick for glass cylinders, the object being to provide a simple and easily operated hand tool for quickly and accurately capping off glass cylinders and for cutting the latter up into smaller sections, and it consists in a handle carrying two permanently fixed contacts and a severing or heating wire permanently attached at one end to one of said contacts and attached at its other end to a reel carried by a frame detachably secured to the handle, and adapted to be brought in engagement with the other contact when the parts are assembled for use.

My invention further consists in the parts and combinations of parts, as will be more fully explained and pointed out in the claims.

In the accompanying drawings, Figure 1 is a view in side elevation partly in section of my improvement; Fig. 2 is an edge view of the same; Fig. 3 is a view of the opposite edge; Fig. 4 is an end view; Fig. 5 is a view in transverse section of the body of the tool in the plane of the plunger 24, the casing of the reel being broken away to show the spring; Fig. 6 is a view showing the manner of using the device.

The body 1 of the tool or capping off stick is oblong and is provided at one end with a handle 2, and at its opposite end with two metal contact blocks 3 and 4, which are separated by suitable insulating material 5 shown in dotted lines in Fig. 1 and in full lines in Fig. 4.

The body of the tool and its handle are made of fiber or other suitable non-conducting material and preferably in three sections, one side including the handle section being formed in a single piece and the opposite side of two parts, the said sections being secured together by screws or other securing means. It is made hollow to contain and conceal the switch 6 and conductor wires 7 and 8, and is cut away or concaved at one

edge to receive the frame 9, carrying the reel 10.

Electric conductors or leading in wires 11 and 11^a are connected respectively with the terminals 12 and 13. Wire 8 is connected with terminal 12, and wire 7 is secured to the switch tongue 6 and is connected up with leading in wire 11^a by the switch lever H. Wire 7 is electrically connected at its opposite end to contact block 3 and wire 8 is connected to contact block 4.

Block 4 is cut away on its outer edge to receive the roller 15 and also to permit the heating wire to pass in approximately 70 straight line to the reel 10, and the block 3 is provided with a hole which passes through the same for the passage of the heating wire, which after passing through said hole, is permanently secured to the screw 17 secured 75 to block 3.

The frame 9 is made of metal and comprises two parallel members carrying a shaft 4^a on which the reel 10 is loosely mounted, but which is connected up to the shaft by a 80 spring 10^a so as to exert a yielding pull on the heating wire 16 and thus hold the same taut and take up any slack caused by the expansion or elongation of the heating wire after it has been heated. The shaft carries 85 a ratchet wheel 18, and a milled thumb wheel 19, and the frame 4 carries a pawl 20 adapted to engage the ratchet wheel 18 and thus hold the same and the shaft against rotation in one direction, the pawl 20 being provided 90 with a projecting end 21 by which it can be readily disengaged from the ratchet wheel, in order to permit the heating wire to be unwound from the reel. One side of the frame is continued up as at 22 and is provided with a hook 23 which is adapted to engage the headed stud 24 carried by the tool or stick 1, and it is locked in place by the spring actuated plunger 25 which latter, when released, enters a notch 26 in the edge 100 of the upwardly projecting portion 22 of the frame 9 and locks the latter on the stud 24.

To remove the frame 9 the plunger 25 is withdrawn thus leaving the hook 23 free to be moved endwise off the stud 24.

In the use of the device the operator disconnects the removable frame 9 and passes the same over the cylinder as shown in Fig. 6. As the frame acts as a weight on the end of the wire, it will be seen, that by a very 110 simple manipulation of the wire, the frame can be swung forwardly under the cylinder

so as to be conveniently reached by the operator, who then passes the hook 23 on the frame over the stud, after which he releases the plunger 25 which moves into the notch 26 in frame 9 and locks the latter to the stick. The cylinders vary but slightly in diameter so that the free wire between the block 3 and the reel is usually sufficient to embrace the cylinder, and any variation in size can be taken care of by letting out wire from the reel or winding up the surplus. After the frame carrying the reel has been secured to the stick, the wire surrounding the cylinder is drawn tightly into contact with the latter, and when so drawn will be under the tension of the spring in the reel, so that the latter will then yieldingly pull on the tightened wire, thus providing for contraction due to cooling and elongation of the wire due to heating. After the wire has been properly applied to the cylinder, the switch lever 14 is moved to close the circuit, and the current passing through the wire 16 rapidly heats the latter, and the heat being communicated to the cylinder causes the same to break or fracture on the heated line. The heating of the wire causes it to elongate, but this elongation is taken care of by the spring in the reel, which winds up the latter and takes up the slack.

In order to heat the cylinder the gap between the wires where the latter engage, the blocks 3 and 4, as shown in Fig. 1, the operator shifts the stick up or down thus carrying the hot wire into contact with the portion of the cylinder that was in the gap. To make another cut, the frame may be removed from the stick and applied as before, or the wire loop embracing the cylinder may be slightly enlarged by letting out some wire and then moving it along the cylinder to the proper point.

It is evident that many slight changes might be resorted to in the relative arrangement of parts shown and described without departing from the spirit and scope of my invention. Hence I would have it understood that I do not wish to confine myself to the exact construction and arrangement of parts shown and described but,

Having fully described my invention what I claim as new and desire to secure by Letters-Patent, is:—

1. A glass severing tool consisting of a body having two terminals for the heating wire, a frame detachably secured to said

body and carrying a reel, a heating wire permanently secured to one terminal and adapted to engage the other terminal at each operation of the tool, the other end of said heating wire being secured to the reel, electric conductors connected with the terminal and a switch for closing the circuit through the conductors and heating wire.

2. A glass severing tool consisting of a body having two terminals for the heating wire, a frame detachably secured to said body, a shaft mounted in said frame, a reel loose on the shaft, a spring connection between the shaft and reel, a heating wire secured at one end to one terminal and engaging the other terminal, the other end of said wire being secured to the reel, electric conductors connected with the terminals and a switch for closing the circuit through the conductors and heating wire.

3. A glass severing tool consisting of a body having two terminals for the heating wire, a frame detachably secured to said body, a shaft mounted in said frame, a ratchet wheel fixed to the shaft, a pawl carried by the frame and engaging the ratchet wheel, a reel loosely mounted on the shaft, a spring connecting the shaft and reel whereby the latter is rotated by the shaft but has a yielding movement thereon, a heating wire secured at one end to one terminal, and at its other end to the reel, electric conductors connected with said terminals and a switch for closing the circuit through the conductors and heating wire.

4. A glass severing tool consisting of a body having two terminals for the heating wire, a frame detachably secured to said body and carrying a shaft, yielding means connecting the shaft and reel whereby the latter may have limited rotation independently of the shaft, a heating wire connected at one end to one terminal and at its other end to the reel, a projection on the second terminal to be engaged by the wire at each operation of the tool, electric conductors leading to the terminals and a switch for closing the circuit leading to the conductors and heating wire.

In testimony whereof, I have signed this specification in the presence of two subscribing witnesses.

WILLIAM R. CAMPBELL.
